PUSH BUTTON SWITCH CONSTRUCTION

Christian Miller, New York, N. Y., assignor to
 Edwards and Company, Inc., a Corporation of
 New York

Application December 16, 1930
 Serial No. 502,649

10 Claims. (Cl. 200—16)

This invention relates to devices for controlling electrical circuits, and more particularly to push button switch construction.

One of the objects of this invention is to provide a compact, rugged and simple push button switch construction that will be of dependable and efficient action in use. Another object is to provide a push button switch construction capable of rapid assembly and inexpensive manufacture and well adapted to withstand the varying conditions of hard practical use. Another object is to provide a simple and reliable push button switch construction adapted particularly to break one circuit and close another circuit when the device is actuated and to provide a construction of this nature in which parts of relatively heavy material may be employed and the circuit-controlling parts dependably maintained in good condition, all without sacrifice of compactness of arrangement and construction and without undue complication. Another object is to provide a construction of the above-mentioned character in which assembly of certain of the moving parts may be dependably maintained in a simple and thoroughly practical and reliable manner. Other objects will be in part obvious or in part pointed out hereinafter.

The invention accordingly consists in the features of construction, combinations of elements, and arrangements of parts, as will be exemplified in the structure to be hereinafter described and the scope of the application of which will be indicated in the following claims.

In the accompanying drawing in which is shown one of various possible embodiments of my invention,

Figure 1 is a side elevation of the assembled push button switch showing the parts in their normal position ready for manual actuation;

Figure 2 is a fragmentary side elevation, as seen from the rear of the device as the latter is shown in Figure 1;

Figure 3 is a vertical central sectional view, as seen along the line 3—3 of Figure 1, and

Figure 4 is an end view, as seen from the right-hand end of Figure 3.

Similar reference characters refer to similar parts throughout the several views of the drawing.

Referring now to the drawing and more particularly to Figures 1 and 3, there is shown a metallic sleeve-like member 10 having a reduced end portion 11 which is exteriorly threaded to receive a threaded collar or nut 12 between which and the shoulder 13 on the sleeve 10 a wall plate,

panel, or any other suitably apertured support may be clamped to hold the assembled push button construction in place.

The sleeve-like member 10 is generally cylindrical in shape and into its larger and right-hand end is fitted and received a substantially cylindrical member 14 made of a suitable solid dielectric material, such as hard rubber, bakelite, or the like, the member 14 being suitably reduced in diameter as at 15 to fit into the right-hand end of the sleeve 10 and having otherwise an outside diameter substantially the same as the outside diameter of the larger portion of the sleeve 10, as is clearly shown in Figures 1 and 3. Suitable securing means, such as screws 16, hold the sleeve 10 and the member 14 in assembled relation.

The member 14 is extended in a direction to the right, as viewed in Figures 1, 2 and 3, and toward the observer viewing Figure 4, as at 17, this extension 17 being of a generally rectangular shape, as viewed in Figure 4, and extending across the right-hand and otherwise circular end of the insulating member 14. The member 17 bulges outwardly in a general radial direction 80 adjacent its middle portion, as at 18, and is preferably integrally formed with the member 14.

Extending centrally through the bulging portion 18 of the extension 17 and preferably aligned with the axis of the otherwise cylindrical insulating member 14 is a hole 19 that is square in cross-section, as is clearly indicated in Figure 4. This hole 19 connects, at its left-hand end (see Figure 3) with a recess 20, preferably round in cross-section, and extending centrally of and along the axis of the insulating member 14.

Slidably guided along the inside cylindrical surface 21 of the reduced portion 11 of the metal sleeve 10 is a push button 22, generally cylindrical in shape and made of any suitable insulating material, such as bakelite, for example. The button 22 has molded into its right-hand end, as viewed in Figure 3, a metal insert 23 that is interiorly threaded to receive the left-hand end of a plunger 24, square in cross-section (see Figure 100 4). Plunger 24 extends in a direction toward the right through the recess 20 in the member 14 and through the square hole 19 in the extension 17, the latter thus nicely guiding the right-hand end of the plunger 24 while the sliding fit of the push button 22 within the portion 11 of the metal sleeve 10 insures a nice guiding of the left-hand end of the plunger 24 as the latter is moved lengthwise of itself either in response to manual pressure exerted in a direction toward the right 110

or in response to the retractive effort of a coil spring 25 that extends about the plunger 24, left-hand end of the spring 25 abutting against the push button 23 and the right-hand end thereof abutting against the extension 17 which extends substantially across the right-hand end of the recess 20.

The right-hand end of the plunger 24 (see Figure 3) has a cylindrical opening 26 extending therethrough and in substantially the same direction in which the extension 17 extends crosswise of the right-hand end of the insulating member 14. Within this recess 26 is received what may be termed a contact-bridging member 27 taking the form of a metal bar of round cross-section, the member 27 having a length substantially the same as the length of the extension 17 in a direction crosswise of the insulating member 14.

Preferably the diameters of the member 17 and of the recess 26 in the plunger 24 are so proportioned that the member 27 is snugly received within the opening 26 so as to nicely align and hold the member 27 at substantially right angles to the axis of the plunger 24. The contact-engaging bar 27 is reduced in diameter as at 28 to provide a space within which the end of a screw 29, threaded into the right-hand end of the plunger 24 may extend. Interposed between the head of the screw 29 and the right-hand end face of the plunger 24 is a lock washer 30 of any suitable construction. The reduction in diameter of the portion 28 and the length of the screw 29 are preferably so proportioned that, when the screw 29 is driven home and securely tightened up to compress the lock washer, the end of the screw 29 does not engage the metal bar 27 though this end of the screw extends sufficiently into the space between the opening 26 and the reduced portion 28 to prevent the member 27 from sliding or from being forced out of the recess 26. By this preferred construction I am enabled to achieve a very dependable permanency and reliability of assembly since the clamping of the lock washer 30 to the end face of the plunger 24 by the action of the relatively large-headed screw 29 provides far greater areas of frictional contact for holding action than could otherwise be provided.

The round bar 27 will be seen to extend to either side of the plunger 24, as is clearly shown in Figures 3 and 4 and its respective ends coat with contact members adapted to be connected into an appropriate electrical circuit or circuits. By way of illustration I have shown one pair of contact members 31-32 with which the contact-bridging member 27 coats when it is held, by spring 25, in the position shown in Figures 1 and 3 and another pair of contact members 33-34 with which the member 27 coats when moved in a direction toward the right as, for example, when the push button 22 is depressed against the action of the spring 25.

Considering now the construction and mounting of these contact members and also certain features of coaction thereof with the contact-bridging member 27, it might first be pointed out that the metal bar or bridging member 27 overlies the transversely extending extension 17, the latter presenting preferably a substantially flat end surface 17^a (Figures 1 and 3) to one side of the square hole 19 and presenting, at its portion on the other side of the hole 19, a concaved surface 17^b (Figures 1 and 2) within which the one end (the upper end, as viewed in Figures 3 and

4) of the contact-bridging bar 27 may be seated under the urge of the coil spring 25. The radius of curvature of the concaved seat 17^b in the extension 17 is preferably the same as the radius of the member 27.

The contact 31, made of a suitable spring sheet metal, such as phosphor-bronze, for example, is generally L-shaped, having a base portion 31^a seated against the right-hand end face of the insulating member 14 and secured to the latter as by screws 35 (see also Figure 4) the base portion 31^a being suitably shaped or curved, as is better shown in Figure 4, to be readily accommodated against the end face of the member 14. Extending at right angles from the base portion 31^a (see Figure 1) is a relatively long arm portion 31^b, the arm portion 31^b extending substantially flatwise along the transverse side face of the extension 17. This arm portion 31^b is bent over substantially upon itself, as at 31^c (see Figure 1) so as to overlap the flat end face 17^a at one side of the extension 17.

The contact member 32 is substantially similarly formed, having a base portion 32^a, secured against the end face of the member 14 by screws 36 and an elongated portion 32^b extending at right angles to the base portion 32^a and along the other transverse side face of the extension 17, being bent over inwardly as at 32^c into overlapping relation with respect to the flat end face 17^a, as is clearly shown in Figure 1.

It is with the bent-over portions 31^c and 32^c that the one end (the lower end, as viewed in Figures 3 and 4) of the bridging member 27 contacts. These portions are urged toward each other, due to the resiliency of the spring metal of which the contact members 31 and 32 are made, and a high degree of spring action of this character is achieved by such features, for example, as the rather substantial length which the arms 31^b and 32^b may be given, as is clearly shown in Figure 1. These arms extend along the respective sides of the extension 17, the latter acting as a stop for limiting the movement of the spring arms toward each other.

The portions 31^c and 32^c are inclined to the longitudinal axis of the construction, thus forming a V-shaped gap into which the contact-bridging member 27 may ride under the urge of the spring 25 when the push button 22 is released, the round cross-section of the member 27 coasting further to insure a ready entry of the member 27 into this V-shaped gap. Moreover, the portions 31^c and 32^c are of substantial length so that, when the member 27 moves into engagement therewith from substantially the dotted line position indicated in Figure 3, a substantial rubbing action between the member 27 and the contact members takes place to insure that the contacting surfaces are bright and clean and can thus establish and maintain dependably the closure of the electric circuit in which the contact members 31 and 32 are connected.

When it its extreme outermost position (the dotted line position shown in Figure 3) the other end portion (the upper end portion, as viewed in Figure 3) is in engagement with portions 33^c and 34^c of the spring contact members 33 and 34, respectively, for closure of the circuit in which these contacts may be included. These portions 33^c and 34^c are substantially parallel to each other and of substantial length, being connected to the side arm portions 33^b and 34^b (see Figure 2) of the spring contacts by inclined portions 33^e and 34^e, respectively, these inclined portions 140

forming V-shaped guides with which the round cross-section of the member 27 effectively coacts when the member 27 is moved in a direction toward the right, upon depression of the push button 22. Such movement of the member 27 brings the latter into engagement with the substantially parallel portions 33^c and 34^c, making an effective rubbing or scraping engagement therewith before coming to rest to insure that the coacting surfaces are clean and bright and thus are capable of maintaining effectively the closure of the circuit in which the contacts are included.

The side portions 33^b and 34^b are connected to base portions 33^a and 34^a (see Figure 4) respectively, these base portions resting flatwise against the right-hand end face of the insulating member 14 (see Figure 1) and being secured thereto by suitable securing devices, such as screws 36, 37 and 38, respectively. The resiliency of the metal of which the contacts 33 and 34 are made merges the latter in a direction toward each other, the extension 17 acting as a stop to limit the movement of these parts toward each other (see Figure 2). The gap between the portions 33^c and 34^c is thus maintained at a minimum and preferably materially less than the diameter of the contact-bridging member 27, the latter in coaction with the inclined portions 33^c and 34^c (Figure 2) causing the separation of the portions 33^c and 34^c to permit the member 27 to enter therebetween.

The member 27 is held in its extreme right-hand position, as shown in dotted lines in Figure 3, as long as the push button 22 is held depressed, the left-hand end face of the reduced portion 15 of the insulating member 14 (see Figure 3) acting as a stop to limit the extent to which the push button 22 may be depressed, the parts being preferably so proportioned that the member 27 is halted in engagement with the portions 33^c and 34^c after having partaken of a rubbing or scraping contact therewith of substantial extent.

When the push button 22 is released the spring 25 moves the parts into the position shown in Figure 3, thus effecting a disengagement of the contact-bridging bar 27 from the contacts 33 and 34 and bringing it into circuit-closing relation to the contacts 31 and 32. The movement of the bar 27 is halted by its engagement with the right-hand end (as viewed in Figures 1, 2 and 3) of the extension 17, one end portion of the member 27 resting against the flat end face 17^a (Figure 1) at one end of the extension 17 and the other end of the member 27 seating itself into the concave end face 17^b at the other transverse end of the extension 17. Thus, the retractive effort of the spring 25 is evenly distributed to and taken up by the opposed portions of the member 27, one on each side of the plunger 24, and thus the parts are nicely maintained in their proper alignment.

The conductors connecting the various contact members into the electrical circuit or circuits in which the device is intended to function may be connected to the contact members in any suitable manner, for example, by utilizing one of the two screws which secures the base portion of each contact member to the insulating member 14; preferably, however, I provide sheet metal lugs 39 (Figure 4) which are held in contact with the contact members by one of the securing screws to permit the conductors to be soldered thereto. Thus, each contact member may individually be associated with a conductor.

It may sometimes be desirable to have one contact member of each pair connected to the same

conductor and in that case I preferably provide a bridging strap 40 (Figure 4) of sheet metal which bridges the base portions of, for example, contacts 34 and 32 and is held in place by the securing screws 36 and 38; in that case a single soldering lug 39 suffices to connect the contacts 32 and 34 to the circuit.

It will thus be seen that there has been provided in this invention a push button switch construction in which the various objects of this invention, together with many thoroughly practical advantages, are successfully achieved. It will be seen that the construction is rugged, compact and of thoroughly dependable action and that it is well adapted to meet the varying conditions of hard practical use. Moreover, it will be seen that a number of circuits may be controlled and that, in the preferred arrangement of the contact, an actuation of the device achieves the closing of one circuit and the breaking of another.

As many possible embodiments may be made of the above invention and as many changes might be made in the embodiment above set forth, it is to be understood that all matter hereinbefore set forth, or shown in the accompanying drawing, is to be interpreted as illustrative and not in a limiting sense.

I claim:

1. In push button switch construction, in combination, a housing made up of a metallic shell having means for securing it to a wall or the like and an insulating member secured to said housing, said member having an opening of polygonal cross-section at its end remote from said shell; a push button slidably supported by said shell and having a plunger of polygonal cross-section extending through said opening in said insulating member; a spring for urging said button in a direction outwardly of said shell; a plurality of pairs of contact members falling within the cross-sectional area of said insulating member and supported exteriorly of said insulating member and aligned crosswise thereof; and a contact-bridging member carried by the end of said plunger for coaction with said pairs of contacts.

2. In push button switch construction, in combination, a housing made up of a metallic shell having means for securing it to a wall or the like and an insulating member secured to said housing, said member having an opening of polygonal cross-section at its end remote from said shell; a push button slidably supported by said shell and having a plunger of polygonal cross-section extending through said opening in said insulating member; a spring for urging said push button in a direction outwardly of said shell; a member carried by said plunger and extending transversely of said insulating member; a plurality of pairs of contact members carried by said insulating member and with which said cross bar coacts, certain of said contacts being arranged to be engaged by said cross bar when the latter is at one point in its stroke and certain other of said contacts being arranged to be engaged by said cross bar when the latter is at another point in its stroke; and an insulating barrier extending between contact members of said pairs.

3. In push button switch construction, in combination, a housing made up of a metallic shell having means for securing it to a wall or the like and an insulating member secured to said housing, said member having an opening of polygonal cross-section at its end remote from said shell; a push button slidably supported by said shell and

having a plunger of polygonal cross-section extending through said opening in said insulating member; a spring for urging said push button in a direction outwardly of said shell; an insulating barrier projecting rearwardly of said insulating member and transversely thereof; a plurality of pairs of contacts associated with said insulating member, certain of said contacts being on one side of said barrier and certain on the other side thereof and one pair of contacts being positioned more remotely from said shell than another pair of contacts; said contacts being fitted into and positioned in the angles between said barrier and the end wall of said insulating member; and means carried by said plunger for successively engaging said contacts as said plunger is moved.

4. In push button switch construction, in combination, a substantially cylindrical insulating member having an opening extending therethrough substantially coincident with its axis and having a rearward extension extending transversely thereof; a plunger passing through said opening and having contact-engaging means extending transversely thereof and substantially overlying said transverse extension; a spring for urging said plunger forwardly of said insulating member; and a plurality of pairs of opposed spring contacts carried by said insulating member for coaction with said contact-engaging means, certain of said spring contacts being positioned at one side of said extension and certain others being positioned at the other side of said extension, the inherent resiliency of said spring contacts urging them toward said extension and said extension limiting the effect of said resiliency.

5. In push button switch construction, in combination, a substantially cylindrical insulating member having an opening extending therethrough substantially coincident with its axis and having a rearward extension extending transversely thereof; a plunger passing through said opening and having contact-engaging means extending transversely thereof and substantially overlying said transverse extension; a spring for urging said plunger forwardly of said insulating member; and a plurality of pairs of spring contacts carried by said insulating member for coaction with said contact-engaging means, certain of said spring contacts being positioned at one side of said extension and certain others being positioned at the other side of said extension, one pair of spring contacts being of a greater length than the other pair of spring contacts so that one pair is engaged by said engaging means at one point in the stroke of said plunger and the other pair is engaged at another point in the stroke of said plunger, and all of said contacts extending beyond the end of said extension, said extension being of such a length that it limits forward movement of said plunger at one of said points in the stroke thereof.

6. In push button switch construction, in combination, a substantially cylindrical insulating member having an opening extending therethrough substantially coincident with its axis and having a rearward extension extending transversely thereof; a plunger passing through said opening and having contact-engaging means extending transversely thereof and substantially overlying said transverse extension; a spring for urging said plunger forwardly of said insulating member; a plurality of spring contacts substantially aligned on one side of said extension and having portions bent inwardly and beyond the

end of said extension and thereby positioned in the path of movement of said contact-engaging means; and a plurality of spring contact members substantially aligned along the other side of said extension and having portions bent inwardly and beyond the end of said extension and thereby positioned in the path of movement of said contact-engaging means, said extension forming means for limiting the movement of certain of said contact members toward each other. 85

7. In push button switch construction, in combination, a housing made up of a metallic shell having means for securing it to a wall or the like and an insulating member of cylindrical shape secured to said housing, the rearmost end of said insulating member having a rearward extension extending centrally transversely thereof and having at its rear end a centrally positioned opening, a push button slidably carried by said metallic shell, a plunger secured to the inner side of said push button and extending through said insulating member and through the opening in the rear end thereof, a spring acting upon said push button and plunger normally to hold them in forward position, a transverse conducting member at the rear end of said plunger, said conducting member overlying said rearward extension on both sides of the opening through said insulating member, said spring normally causing said conducting member to be seated against said rearward transverse extension, a pair of L-shaped spring contacts fitted into the angle between the rear face of said insulating member and a side face of said rearward extension, a pair of L-shaped contact members fitted into the angle between the other side face of said rearward extension and the end face of said insulating member and respectively juxtaposed to said first-mentioned contact members, all of said contact members extending beyond said extension and being inherently resilient and urged toward said extension, and all of said contacts having portions positioned in the path of movement of said transverse conducting member on said plunger, and means securing said contact members to said insulating member. 105

8. In push button switch construction, in combination; a substantially cylindrical insulating member having an opening extending therethrough substantially coincident with its axis and having a rearward extension extending transversely thereof; a plunger passing through said opening and having contact-bridging means extending transversely thereof and substantially overlying said transverse extension; a plurality of pairs of spring contacts carried by said insulating member, said contacts extending alongside of said extension and beyond the latter and having their end portions shaped to be engaged by said contact-bridging means when the latter is moved by said plunger; means for preventing rotation of said plunger; and a spring acting on said plunger in a direction normally to seat it against said extension. 125

9. In push button switch construction, in combination, a substantially cylindrical insulating member having an opening extending therethrough substantially coincident with its axis and having a rearward extension extending transversely thereof; a spring-retracted plunger passing through said opening and having contact-bridging means extending transversely thereof and substantially overlying said transverse extension; means for preventing rotation of said plunger, thereby to hold said bridging means 145

aligned with said extension; and a pair of spring contact members, one on each side of said extension and yieldably urged toward the latter, said contact members extending beyond the end 5 of said extension and in the path of movement of said contact-bridging member.

10. In push button switch construction, in combination, insulating means supporting a plurality of contact members, a plunger movable 10 relative to said insulating means and having

an opening therein through which extends a contact-engaging member recessed intermediate its ends; a screw extending through a portion of said plunger and into the recess of said contact-engaging member, and means for locking said screw to said plunger, said screw being of a length insufficient to clamp said contact-engaging member. 80
